UNITED STATES PATENT OFFICE.

CHARLES W. HODSDON AND GEORGE B. GERAU, OF NEW YORK, N. Y.

SEWING-MACHINE NEEDLE.

SPECIFICATION forming part of Letters Patent No. 623,666, dated April 25, 1899.

Application filed December 8, 1897. Serial No. 661,168. (No model.)

To all whom it may concern:

Be it known that we, CHARLES W. HODSDON and GEORGE B. GERAU, citizens of the United States, residing at New York, (Brooklyn,) in the county of Kings and State of New York, have invented certain new and useful Improvements in Sewing-Machine Needles, of which the following is a full and complete specification, such as will enable those skilled in the art to which it appertains to make and use the same.

This invention relates to sewing-machine needles; and the object thereof is to provide a needle of this class with simple and improved means for facilitating the threading thereof without being compelled to insert the thread through the eye of the needle.

The invention is fully disclosed in the following specification, of which the accompanying drawing forms a part, in which the separate parts of our improvement are designated by letters of reference, said drawing being a front elevation of our improved needle.

Referring to the drawing, A represents the body of an ordinary sewing-machine needle, which is provided with the usual enlarged cylindrical head a. That portion of the needle which connects the head a with the body thereof is conical in form, as shown at a², and the needle A is provided at the usual distance above the point a³ with the eye a⁴, which is oblong in form, the longer diameter thereof being in line with the longitudinal center of the needle. The needle A is also provided with the usual longitudinal groove a⁵, which is formed in one side thereof and which extends along said side from the eye a⁴ to the head a of the needle, and our improved means for facilitating the operation of threading the needle comprises a longitudinal slot a⁶, formed in the needle parallel with and adjacent to one side of the longitudinal center thereof, and the lower end of said slot is curved inwardly and communicates with the eye of the needle by passing through one of the side walls thereof, as shown at a⁷, and the upper end of said slot communicates with the upper end of a downwardly and outwardly inclined supplemental slot a⁸, which is, as shown in the drawing, formed in the conical portion a² at the lower end of the head a. This down-

wardly and outwardly inclined slot, however, may be formed in the upper end of the body portion A of the needle or in the head a, if desired, the only object in this connection being to form said supplemental slot a⁸ at a downward and outward inclination, so as to communicate with the upper end of the slot a⁶ wherever that may be, a further object being to form the slot a⁸ at or near the upper end of the needle, so that it will not interfere with the operation thereof.

The slot a⁸ opens outwardly, as will be readily understood, and in threading the needle the thread is passed upwardly into said slot, to the upper end thereof, where it communicates with the longitudinal slot a⁶, and the thread is passed downwardly through said slot a⁶ and into the eye of the needle, as will be readily understood. The slot a⁶ communicates with the eye of the needle, below the upper end thereof and above the lower end, and does not interfere with the operation of the needle in forcing the thread downwardly through the cloth or fabric or in drawing it upwardly through said cloth or fabric.

The side strip B of the needle, formed by the slot a⁶ and the supplemental slot a⁸, possesses slight spring qualities, as will be readily understood, and the thread is therefore free to pass through the slot a⁶, and by reason of the supplemental slot a⁸ the upper end of the said side strip is always held in position and cannot be thrown outwardly or misplaced radially in the operation of the needle.

Our improvement is simple in construction and operation and perfectly adapted to accomplish the result for which it is intended and does not add materially to the cost of the needle.

Having fully described our invention, we claim as new and desire to secure by Letters Patent—

A sewing-machine needle provided with a cylindrical head, that portion of the needle which is connected with the head being conical in form, said needle being also provided with the usual eye, and a longitudinal slot which is formed in one side of said needle, and the lower end of which communicates with the eye of the needle, and the upper end of which terminates at or near the conical

portion adjacent to the head thereof, and communicates with a downwardly and outwardly inclined supplemental slot which opens outwardly through the side of the needle, whereby 5 a spring side piece is formed integral with the needle, the upper end of which is held in place by the upper wall of the supplemental slot, substantially as shown and described.

In testimony that we claim the foregoing

as our invention we have signed our names, ¹⁰ in presence of the subscribing witnesses, this 4th day of December, 1897.

CHARLES W. HODSDON.
GEO. B. GERAU.
